WISCONSIN, A CORPORATION OF DELAWARE.

PRIME-MOVER-CONTROL SYSTEM.

Application filed June 23, 1924. Serial No. 721,660.

This invention relates to control systems for prime movers.

One of the objects of the invention is to provide a system whereby a prime mover may 5 be automatically slowly started and brought to normal running condition. Another object is to provide a control system whereby a prime mover may be slowly stopped and the means for admitting operating fluid thereto 10 closed without shock.

A more specific object is to provide a prime mover control system in which a restricted application of power to the gate or other means for admitting operating fluid to the 15 prime mover is provided for while starting or stopping the prime mover, to cause slow motion of said gate. Another more specific object is to provide means performing one or more of the aforesaid results in combination 20 with a governor for the prime mover comprising fluid pressure operated motive devices. Other objects will be apparent hereinafter as the description of the invention proceeds.

25 The novel features of the invention will appear from this specification and accompanying drawing forming a part thereof and disclosing one embodiment of said invention, and all these novel features are intended to 30 be pointed out in the claims.

35 The single figure of the drawings is a diagrammatic showing of the manner in which the invention may be applied in combination with a hydraulic turbine and governor therefor.

Referring to the drawing the prime mover here shown is a hydraulic turbine 1 which may, through shaft 2, drive a generator 3. The turbine 1 is supplied with water through a 40 pipe 4 in which is mounted a valve or gate 5 pivoted at the point 6. It is to be understood that the admission of water to turbine 1 may be controlled in any other suitable manner as for example by the usual guide vanes. For 45 the sake of brevity the means for controlling the admission of operating fluid to the turbine or other prime mover will be called a gate hereinafter. Gate 5 is adapted to be operated by means of a crank 7 connected by rod 8 to a servo-motor including pistons 9, 10 here shown as operating in unison in two independent cylinders. Other suitable forms

of motors may be utilized. The pistons 9, 10 may be operated by admitting fluid under pressure to one or the other of the cylinders as 55 the case may be, and such admission of fluid may be controlled by a regulating valve 11. The regulating valve is provided with spaced piston valves 12, 13 operating in a cylinder 16. When the regulating valve 11 is in its 60 neutral position piston valves 12, 13 close ports 14, 15 in cylinder 16, respectively. The cylinder 16 is provided with drain ports 17, 18 suitably positioned with respect to piston valves 12, 13. These drain ports may be connected in any suitable manner with a receiving tank 19 from which latter oil may be drawn by means of a pump 20 and discharged into a pressure tank 21. A pipe 22 leads from pressure tank 21 to a shut-off valve 23 which 70 in the position of the parts shown, closes communication between pipe 22 and another pipe 24 which is connected through a port to cylinder 16, the port being shown between piston valves 12, 13. The shut-off valve 23 is 75 here shown as operable to open position by means of a piston 25 normally held in the position shown by means of a spring. Fluid under pressure may be admitted, through a pipe 26, above piston 25 to move the same 80 against the bias of a suitably disposed restraining spring. An electro-magnetically operated valve 27 provided with an operating coil 28 is adapted when effectively actuated to open communication between pipe 26 85 and another pipe 29 connected to pipe 22.

The regulating valve 11 is operatively related through a rod 30 carrying the piston valves 12, 13, with a floating lever 31. The floating lever 31 carries at one end a swivel nut 90 32 through a hole in which the rod 30 is adapted to pass. Rod 30 carries a collar 33 pinned thereto and a spring 34 is disposed about rod 30 between collar 33 and swivel nut 32. The upper end of rod 30 is threaded and provided 95 with a suitably locked adjustable nut 35 whereby the rod 30 may be lifted by floating lever 31 when nut 32 abuts nut 35. Loosely disposed around rod 30 is a sleeve or collar 36, here shown as provided with a cylindrical extension loosely surrounding the collar 33. This cylindrical extension may however be dispensed with. A spring 37 is disposed 100 between collar 33 and the loose collar 36.

When spring 37 is not compressed as shown it sets collar 36 up against another collar 38 pinned to shaft 30.

The regulating valve 11 is adapted to be controlled independently of floating lever 31 and for this purpose the collar 36 is here shown as provided with a projection 39 adapted to be engaged by a control finger 40. It is of course to be understood that the illustrated embodiment is merely one way in which control finger 40 may affect regulating valve 11, and that also the connection between the regulating valve and the floating lever may be varied in any desirable manner. Control finger 40 tends to be biased out of engagement with projection 39 by means of a spring 79. Rigidly associated with control finger 40 is a lever 41 provided at one end with a portion having a hole 42 through which a rod 43 is adapted to pass. One end of rod 43 is provided with an adjustable nut 44 adapted to abut against lever 41. Rod 43 is pivoted to one arm of a bell crank lever 45, the other arm of which is connected by means of a rod 46 to a crank 47 operating in unison with the gate 5. The connection between gate 5 and control finger 40 through rod 43 and the associated parts constitutes a load limiting device.

The shut-off valve 23 may be by-passed by a pipe 48 and a pipe 49 in a manner to be now described. The pipe 48 connected to pipe 22 is connectible, through a valve 51 with the pipe 49 communicating with a port 50 in cylinder 16. Valve 51 includes a valve member 52 operable in a cylinder 56 provided with a channel 53 adapted, when the valve member 52 is raised, to place a port 54 communicating with pipe 49 and a port 55 communicating with pipe 48 in communication.

The position of valve member 52 may be accentuated either in its closed or open positions by means of a ball 57 which is adapted, in the position of the parts shown, to engage an annular notch 58 in the valve member 52.

Movement of the valve member 52 upwardly presses the ball 57 against a biasing spring and when the valve is open the ball 57 will snap into another notch 59 in the valve member 52. The valve member 52 is provided

with an operating rod 60 passing through said valve member with a sliding fit. The rod 60 is provided with a collar 61 fixed thereto adapted to engage the upper end of valve member 52. Rod 60 is provided with

another collar 62 fixed thereto and adapted, when the rod 60 is moved upwardly a predetermined distance, to engage the lower end of valve 52. The operating rod 60 may be raised by means of a piston 63 biased to the position shown in any suitable manner, as by a spring 87. The piston 63 is operable in a cylinder 64 to which fluid under pressure may be admitted through a pipe 65. For the purpose of controlling the admission of fluid under pressure to pipe 65 there is here shown

an electromagnetically operated valve 66 provided with an operating coil 67 which when effectively actuated opens communication between pipe 65 and a pipe 68 connected to pressure tank 21 as through pipe 48.

The amount of fluid under pressure which may flow through by-pass 48-49 may be regulated as by a reducing valve 69.

The operating means for valve 51 is here shown as also performing another function, namely, exercising a control on regulating valve 11, though separate means may be employed. For this purpose the upper end of rod 60 is suitably pivotally connected to a lever 70 rotatable about pivot 86 independently of levers 40, 41. When lever 70 is swung in a counter-clockwise direction, as viewed in the drawing, it abuts against an adjustable screw 71 carried by a lever 72 operating in unison with lever or control finger 40. At the pivotal connection between operating rod 60 and lever 70 a roller 73 is provided which acts as a detent cooperable with a latch 74 pivoted at the point 75. Operable in unison with latch 74 is a lever 76 biased, by means of a spring 77, in such direction that when roller 73 is lifted sufficiently high, latch 74 will swing to a position where reverse movement of rod 60 will be stopped by engagement with roller 73 with latch 74. The latch 74 may be stopped in engaging position by means of a stop 88 and an extension 89 on latch 74. In the position of the parts shown a collar 78 rigidly attached to rod 43 is shown as in engagement with lever 76 in which position of the parts the latch 74 has been moved out of engagement with roller 73.

The floating lever 31 is provided with a floating pivot 80 to which is connected in any suitable manner the flyball mechanism 81 driven in any desired manner, as by means of belt 82 from shaft 2, so that the flyball mechanism will be responsive to the speed of the turbine or generator. To one end, 83, of the floating lever is pivoted the piston rod 110 of a compensating or dash pot device 84 which may be of any suitable and desired form. The lower end of the compensating device 84 is pivotally connected to a lever 85 operating in unison with lever 45.

The operation is as follows: Assuming the parts to be in the position shown in the drawing and that magnet or coil 67 is then energized, as for example by means of the closure of a switch located at any desired point; the valve 66 will rise and place pipes 65 and 68 in communication so that fluid under pressure is admitted to cylinder 64 from pressure tank 21. Piston 63 therefore slowly rises and swings lever 70 in a clockwise direction thereby permitting control finger 40 to also follow in a clockwise direction under the influence of spring 79 and springs 34, 37. The regulating valve rod 30 therefore slowly moves the piston valves 12, 13 toward neutral position.

Continued upward movement of piston 63 moves the regulating valve to just beyond neutral position in which fluid under pressure may be admitted through port 15 to move piston 10 to the right to open gate 5. When piston 63 has thus moved the regulating valve just beyond neutral position toward the gate-open position, collar 62 reaches the lower end of piston valve 52. Before this point in the travel of piston 63 the roller 73 has been raised high enough so that latch 74, if permitted to swing in a counter-clockwise direction, will be beneath roller 74 and in a position to engage said roller so as to prevent return movement of piston 63 for a purpose to be set forth hereinafter. Further movement of piston 63 in an upward direction will cause collar 62 to move valve member 52 to a position where the channel 53 places ports 54, 55 in communication. In this position the accentuating roller 57 is snapped into notch 59. A restricted quantity of fluid under pressure is now admitted through by-pass 48, 49 and port 50 to the regulating valve, which has been meanwhile moved further toward gate-open position, thereby admitting some fluid under pressure to the cylinder of piston 10 thus moving gate 5 toward open position. A very slight opening movement of gate 5 will cause rod 46, through lever 45, to move collar 78 away from lever 76 thereby permitting latch 74 to move, under the influence of spring 77, to a position where it is ready to be engaged by roller 73 upon any return movement of rod 60. When the turbine 1 has started by reason of the opening of gate 5 the fly balls 81 will, depending upon their adjustment, begin to exert an influence on regulating valve 11 through floating lever 31 to control the speed of the turbine. It will therefore be evident that the control finger 40 has completely released regulating valve 11 and the turbine is under speed control. When the turbine has reached normal speed or gate 5 has been fully opened, or the generator 3 has been connected to the line, coil 28 may be energized. Coil 28 may of course be energized under any other desired predetermined conditions. Energization of coil 28 opens communication between pipes 29 and 26 thereby causing the shut-off valve 23 to move to open position in which it connects pipes 22 and 24. The passage through pipes 22, 24 is large enough to admit the normal quantity of fluid under pressure to regulating valve 11, and therefore to the servo-motor, so that the servo-motor may operate gate 5 more rapidly. The controlling influence of the fly balls upon gate 5, through the action of regulating valve 11, will therefore take place more rapidly so that the speed of turbine 1 will be maintained constant under load conditions. When gate 5 has reached a predetermined open position, nut 44 will engage the portion 42 of lever 41. If regulating valve 11 is in gate-open position,

further movement of nut 44 will swing control finger counter-clockwise thus moving regulating valve to neutral position and stopping further opening movement of gate 5. Such control of the regulating valve by nut 44 is possible because lever 70 is independent of levers 40, 41 and it does not therefore, interfere with the operation of the load limiting means.

The operation of the system when it is desired to stop the turbine is as follows: Coils 28 and 67 are deenergized. The deenergization of coil 28 causes closing of the shut-off valve 23. The only path for fluid under pressure to the regulating valve and servomotor is therefore through by-pass 48, 49. The deenergization of coil 67 closes valve 66 thereby permitting piston 63 to descend under the influence of spring 87. Downward motion of piston 63 causes counter-clockwise motion of control finger 40 thereby compressing springs 37 and 34 and when the regulating valve 11 has been moved just beyond neutral position toward gate-closed position the roller 73 will engage latch 74. At this time 90 collar 61 is in engagement with or ready to engage valve member 52 but has not moved the latter which is still in the open position permitting fluid under pressure to pass through by-pass 48, 49. This fluid passes 95 through the regulating valve 11 and into the cylinder of piston 9 thereby slowly closing gate 5. When gate 5 has nearly reached its closed position collar 78 engages lever 76 and further movement swings lever 76 in a clockwise direction thereby releasing latch 74. Spring 87 is therefore free to move collar 61 against valve member 52 to close the same. This brings the parts to the same position as shown in the drawing.

It should be understood that it is not desired to limit the invention to the exact details of construction shown and described, for obvious modifications may occur to persons skilled in the art.

It is claimed and desired to secure by Letters Patent:

1. In a control system for a prime mover, a gate for controlling the admission of operating fluid to said prime mover, means including fluid pressure operated means for operating said gate, a control valve for said fluid pressure operated means, and means for supplying said control valve with a restricted quantity of fluid under pressure and supplying a larger quantity under predetermined conditions, the pressure of the source of supply remaining substantially constant.

2. In a control system for a prime mover, 125 a gate for controlling the admission of operating fluid to said prime mover, a governor for said prime mover including a servomotor for said gate and means responsive to the speed of said prime mover for controlling 130

said servo-motor, means for supplying a quantity of fluid under pressure to said governor sufficient to enable it to perform its normal regulating function, and means for restricting said supply when said prime mover is being started or stopped.

3. In a control system for a prime mover, a gate for controlling the admission of operating fluid to said prime mover, a governor for said prime mover including a servo-motor for said gate and a regulating valve therefor, means for supplying fluid under pressure to said regulating valve, and common means operable independently of said governor for controlling the position of said regulating valve and the supply of fluid pressure thereto.

4. In a control system for a prime mover, a gate for controlling the admission of operating fluid to said prime mover, a governor for said prime mover including a servo-motor for said gate and a regulating valve therefor, means for supplying fluid under pressure to said regulating valve, means for controlling the position of said regulating valve and the supply of fluid pressure thereto, and means for depriving said last named means of its control of the supply of fluid pressure.

5. In a control system for a prime mover, a gate for controlling the admission of operating fluid to said prime mover, a governor for said prime mover including a servo-motor for said gate and a regulating valve therefor, means for supplying fluid under pressure to said regulating valve, common means operable independently of said governor for controlling the position of said regulating valve and the supply of fluid pressure thereto, and means responsive to the position of said gate for controlling said last named means.

6. In a control system for a prime mover, a gate for controlling the admission of operating fluid to said prime mover, a governor for said prime mover including a servo-motor for said gate, a control valve for said servo-motor, means for supplying fluid under pressure to said control valve, means for controlling said supply of fluid under pressure, and means for depriving said last named means of its control of said fluid pressure supply.

7. In a control system for a prime mover, a gate for controlling the admission of operating fluid to said prime mover, a governor for said prime mover including a servo-motor for said gate, a control valve for said servo-motor, means for supplying fluid under pressure to said control valve, means for controlling said supply of fluid under pressure, means for initially actuating said fluid pressure supply controlling means independently of said gate and while said governor is at rest, and means responsive to the position of

said gate for controlling said last named means.

8. In a system for controlling a prime mover, a gate for controlling the admission of operating fluid to said prime mover, a servo-motor for said prime mover operatively related to said gate and a regulating valve thereof, means operatively related to said regulating valve for predetermining the maximum gate opening, means for supplying fluid under pressure to said regulating valve, and means for restricting said fluid pressure supply under predetermined conditions.

9. In a system for controlling a prime mover, a gate for controlling the admission of operating fluid to said prime mover, a servo-motor for controlling said gate, a valve for controlling the admission of fluid under pressure to said servo-motor, means for holding said valve in open position, and means operated by said gate for releasing said holding means.

10. In a system for controlling a prime mover, a gate for controlling the admission of operating fluid to said prime mover, a servo-motor for controlling said gate, a regulating valve for said servo-motor having a gate-closed and neutral position, a second valve for controlling the admission of fluid under pressure to said servo-motor, means for moving said regulating valve to a position toward gate-closed position a predetermined amount beyond neutral position, means for holding said second valve in open position, and means responsive to the position of said gate for releasing said holding means.

11. In a system for stopping a prime mover, a gate for controlling the admission of operating fluid to said prime mover, fluid pressure operated means for operating said gate, means for supplying fluid under pressure to said gate-operating means to close said gate, and means responsive to a predetermined gate-position for cutting off said supply of fluid pressure.

12. In a system for starting a prime mover, a gate for controlling the admission of operating fluid to said prime mover, fluid pressure operated means for operating said gate, means for admitting a supply of fluid under pressure to said last named means sufficient to slowly open said gate, means responsive to the speed of said prime mover and permitting it to rise to a predetermined value, and means for then increasing the supply of fluid under pressure.

13. In a system for starting a prime mover, a gate for controlling the admission of operating fluid to said prime mover, fluid pressure operated means for operating said gate, means for admitting a supply of fluid under pressure to said last named means sufficient to slowly open said gate, means responsive to the speed of said prime mover and permit-

ting it to rise to a predetermined value, means for then increasing the supply of fluid under pressure, and means for predetermining the maximum gate opening.

5 14. In a control system for a prime mover, a gate for admitting operating fluid to said prime mover, a servo-motor for operating said gate, a regulating valve for said servo-motor, a member operatively related to said regulating valve and biased to move said valve to gate-open position, a member positioned in accordance with the position of said gate and having a lost motion connection with said first named member, and a motive 10 device for moving said first named member toward gate-open position and having a lost motion connection therewith, and a valve for controlling a supply of fluid under pressure to said regulating valve operatively related 15 to said motive device.

15. In a control system for a prime mover, a gate for admitting operating fluid to said prime mover, a servo-motor for operating said gate, a regulating valve for said servo- 20 motor, a member operatively related to said regulating valve and biased to move said valve to gate-open position, a member positioned in accordance with the position of said gate and having a lost motion connection 25 with said first named member, and a motive device for moving said first named member toward gate-open position and having a lost motion connection therewith, and a valve for controlling a supply of fluid under pressure 30 to said regulating valve operatively related 35 to a lost motion connection to said motive device.

16. In a control system for a prime mover, a gate for admitting operating fluid to said prime mover, a servo-motor for operating said gate, a regulating valve for said servo-motor, a member operatively related to said regulating valve and biased to move said valve to gate-open position, a member positioned in accordance with the position of 40 said gate and having a lost motion connection with said first named member, and a motive device for moving said first named member toward gate-open position and having a lost motion connection therewith, a valve for controlling a supply of fluid under pressure to said regulating valve operatively related to 45 said motive device by a lost motion connection and opened by a predetermined travel of said motive device, and means for preventing reclosure of said valve, after said lost motion has been taken up, by reverse movement of said motive device.

50 17. In a gate-control system for a prime mover, a servo-motor regulating valve, a valve for controlling the admission of fluid under pressure to said regulating valve comprising, a valve-member, an operating member for said valve member having a lost motion connection therewith, a detent on said

operating member, a latch positioned to be engageable with said detent when said operating member has substantially taken up said lost motion toward valve-open position and a connection between said operating 70 member and said regulating valve.

18. In a gate-controlling system for a prime mover, a gate operating control-means including, a control member, an operating member for said control member having a 75 lost motion connection therewith, a detent on said operating member, and a latch positioned to be engageable with said detent when said operating member has substantially taken up said lost motion.

19. In a gate-control system for a prime mover, a servo-motor regulating valve, a valve for controlling the admission of fluid under pressure to said regulating valve comprising, a valve-member, an operating member for said valve member having a lost motion connection therewith, a detent on said operating member, a latch positioned to be engageable with said detent when said operating member has substantially taken up said 80 lost motion toward valve-open position and a connection between said operating member and load limiting means connected to said regulating valve, and means, connecting said operating member with said regulating valve, 85 whereby said operating member causes movement of said regulating valve during the starting and stopping periods while permitting control of said regulating valve during the running period of said prime mover.

100 20. In a control system for a prime mover, a gate for controlling the admission of operating fluid to said prime mover, means including fluid pressure operated means for operating said gate, a control valve for said fluid pressure operated means, a shut-off valve which when open admits a normal quantity of fluid under pressure to said control valve, a bypass around said shut-off valve, and means in said bypass whereby a 105 restricted quantity of fluid under pressure may be admitted to said control valve when said shut-off valve is closed.

110 21. In a control system for a prime mover, a gate for controlling the admission of operating fluid to said prime mover, means including fluid pressure operated means for operating said gate, a control valve for said fluid pressure operated means, means responsive to the speed of said prime mover operatively related to said control valve, means for biasing said control valve toward the gate-open position when said prime mover is at rest, means for permitting said bias to become effective under predetermined conditions, and means operated by said last named means for admitting fluid under pressure to said control valve.

115 22. In a control system for a prime mover, a gate for controlling the admission of oper- 120
